UNITED STATES PATENT OFFICE.

CHARLES E. HOFFMAN, OF RICHLAND, WASHINGTON.

SAFETY DELIVERY RECEPTACLE.

Application filed June 12, 1926. Serial No. 115,477.

This invention relates to safety delivery receptacles and has for one object to provide for the sanitary, safe and theft-proof storage of bottles containing milk or cream.

Another object of this invention is to provide, in receptacles of the class described, a means for the safe storage of empty milk or cream bottles so as to permit the ready removal of same from said receptacle.

With the above and other objects in view, the invention consists of the combination and arrangement of parts and in the details of construction hereinafter described and claimed, it being understood that, within the scope of what is claimed, changes in the precise embodiment of the invention shown can be made without departing from the spirit of the invention.

In the drawing—

Figure 1 is an elevation in perspective of the invention;

Figure 2 is a side elevation with the wall removed;

Figure 3 is an elevation of the inside of the door.

In the accompanying drawings a preferred form of my invention is shown, in which 1 refers to a cabinet of suitable material, preferably wood, and having one open side 30 wherein is positioned the door 2 mounted on the hinges 3 to swing horizontally and having intermediate its free edge the key hole 4 and on its inside face the lock 5 so as to coincide suitably with the said keyhole, said lock having the lock bolt 6 which is caused to advance from its upper side by means usual to such locks suitably to make contact with the right angularly projecting finger 7 of the upper arm of the bell crank 8, preferably constructed of a flat metal bar and having on its lower arm the right angularly projecting finger 9 shaped to form the hook 10 having an inclined or cam shaped face 11 thereon that causes the said hook to automatically engage with the lip 16 hereinafter described. The said bell crank 8 is rotatably mounted on the pin 12 affixed to the door 2, the said pin 12 being positioned to one side of the center of gravity of the said bell crank 50 8 so as to cause the said bell crank to normally assume the position shown but free to rotate under the influence of other agencies as hereinafter described. The side walls of the cabinet 1 have provided therein the holes 55 13^a positioned near the bottom of said cabinet and between the center and the open side of

said cabinet, said holes having affixed therein the rod 13. Resting upon the rod 13 is the false bottom 14 constructed of a metal plate of dimensions slightly smaller than the inside of the said cabinet 1, and having formed thereon the lips 15 suitably positioned so as to confine the said false bottom 14 against transverse movement relative to the rod 13 but permitting the said false bottom 14 to be 65 lifted vertically from the rod 13 and removed for cleaning. Also formed on the said false bottom 14 is the lip 16 positioned intermediate the front edge thereof.

The said false bottom 14 is mounted in the 70 said cabinet 1 so as to be pivoted nearer its front edge than its back edge, as is obvious from the position of the aforementioned rod 13. It is obvious that the said false bottom 14 will incline rearwardly by the action of 75 gravity; means for restraining the pivoting motion of the said false bottom are provided as hereinafter described, whereby the said false bottom will be caused to take a horizontal position by the weight of an article, such 80 as the milk bottle 17, when the said article is placed on the said false bottom forwardly the said pivoting means or rod 13. When in the said horizontal position the said false bottom co-operates with the before described 85 locking means provided on the said door 2 so as to releasably latch the said door 2 to the said false bottom 14, as will now be described.

When a bottle 17 containing milk or cream 90 is placed on the false bottom 14 so as to be positioned outwardly from the rod 13, the weight of the said bottle 17 causes the false bottom 14 to rotate about the rod 13 so as to take a horizontal position, said rotation 95 being restrained by the engagement of the inside edge of the said false bottom 14 with the right angularly projecting finger 18 of the stop 19 affixed to the inside of the rear wall of the cabinet 1. When the said false 100 bottom 14 is in a horizontal position as above described and the door 2 is closed the lip 16 engages with the cam shaped face 11 thereby causing the bell crank 8 to rotate about the pin 12 so as to permit the hook 10 105 to latch under the lip 16 thereby causing the door 2 to be held in a closed position, but when the bolt 6 of the lock 5 is caused to advance upwardly by means usual to such locks, the said bolt 6 will engage the finger 7 there- 110 by causing the bell crank 8 to rotate about the pin 12 so as to unlatch the hook 10 from

the lip 16 thereby permitting the door 2 to be opened and the bottle 17 removed from the receptacle. The false bottom 14 will then rotate about the rod 13 so as to take a position inclined rearwardly, said rotation being restrained by the engagement of the inside edge of the false bottom 14 with the floor of the said cabinet 1 thereby causing the lip 16 to move vertically upward so as to be prevented from engaging the hook 10 when the said hook 10 is returned to its normal position. When empty bottles are placed in the receptacle they should be positioned on the false bottom 14 so as to be rearward of the rod 13 thus permitting the said false bottom 14 to remain in a rearwardly inclined position. When the bolt 6 is caused to be withdrawn into the lock 5, thus permitting the ball crank 8 to return to its normal position, it is obvious that the hook 10 will not engage the lip 16 and latch the door 2 until the false bottom 14 is caused to take a horizontal position in the manner heretofore described. The rear wall of the cabinet 1 has provided therein the holes 20 whereby the receptacle may be supported on a wall or otherwise as desired. Also is provided the knob 21 positioned intermediate the free edge of the door 2 and on the outside thereof for convenience in opening said door.

For convenience in description and illustration I have shown the invention carried

forth with a cabinet of wood and fittings and appurtenances of metal; however, it is obvious that the invention is not limited in practice to such materials but may be also constructed entirely of metal.

I claim:

In a device of the kind described, the combination with a cabinet, a door hingedly mounted on the said cabinet, and a false bottom pivoted in the said cabinet, of a locking means comprising a lock; a lock bolt provided in the said lock and adapted to advance upwardly from the said lock; a bell crank pivoted on the said door; a right angularly projecting finger provided on the upper arm of the said bell crank; the said projecting finger being adapted to engage the said lock bolt when the said lock bolt is advanced upwardly from the said lock; a right angularly projecting finger provided on the lower arm of the said bell crank; an inclined or cam shaped face provided on the second mentioned projecting finger so as to form a hook; a downwardly projecting lip positioned on the forward edge of the said false bottom; the said lip being adapted to engage the said hook whereby the said door may be latched to the said false bottom.

In testimony whereof I affix my signature.

CHARLES E. HOFFMAN.
